COMBINED KNIFE, SAW, AND FORK

Kenneth G. Niblack, Buffalo, N. Y.

Application March 29, 1954, Serial No. 29,756

Term of patent 14 years

(Cl. D22—3)

To all whom it may concern:

Be it known that I, Kenneth G. Niblack, a citizen of the United States and a resident of Buffalo, New York, have invented a new, original, and ornamental Design for a Combined Knife, Saw, and Fork, of which the following is a specification, reference being had to the accompanying drawing, forming a part thereof.

Fig. 1 is a side elevational view of a combined knife, saw, and fork showing my new design;

Fig. 2 is a top plan view; and

Fig. 3 is a sectional view thereof taken along the line 3—3 of Fig. 1.

The essential features of my design reside in

the portions shown in solid lines on the drawing.

I claim:

The ornamental design for a combined knife, saw, and fork, as shown and described.
